Primary Examiner — Stella Reid*Assistant Examiner* — Wan Laymon(74) *Attorney, Agent, or Firm* — Nixon & Vanderhye P.C.**CLAIM**

The ornamental design for a mask, as shown and described.

DESCRIPTION

FIG. 1 is a perspective view of a mask according to an embodiment of our design;

FIG. 2 is a front view thereof;

FIG. 3 is a rear view thereof;

FIG. 4 is a top view thereof; and,

FIG. 5 is a left side view thereof.

The broken lines show environment or structure of the mask and form no part of the claimed design.
